(57) **CLAIM**

The ornamental design for a pulmonary artery stent, as shown and described.

DESCRIPTION

FIG. 1 is an isometric perspective view of the pulmonary artery stent;

FIG. 2 is the front view thereof;

FIG. 3 is the rear view thereof;

FIG. 4 is the top view thereof;

FIG. 5 is the bottom view thereof;

FIG. 6 is left-side view thereof;

FIG. 7 is right-side view thereof;

FIG. 8 shows a deformed view thereof;

FIG. 9 shows an enlarged isometric perspective view of the enclosed area of FIG. 1; and,

FIG. 10 shows an enlarged view of the enclosed area of FIG. 2.

The broken lines in FIG. 1 are for the purpose of illustrating the end of the pulmonary artery stent, shown in FIG. 9 and form no part of the claimed design.

The broken lines in FIG. 2 are for the purpose of illustrating the end of the pulmonary artery stent, shown in FIG. 10, and form no part of the claimed design.

The broken lines in FIG. 9 define the bounds of the claimed design and form no part thereof.

The broken lines in FIG. 10 define the bounds of the claimed design and form no part thereof.
